UNITED STATES PATENT OFFICE.

CHARLES FREBORG AND CASPER JELLY, OF RICHMOND, INDIANA, ASSIGNORS TO THE STARR PIANO COMPANY, OF RICHMOND, INDIANA, A CORPORATION OF INDIANA.

CHROMATIC GLISSANDO KEYBOARD AND METHOD OF PLAYING THE SAME.

Application filed July 1, 1927. Serial No. 202,807.

This invention relates to keyboards and to a method of playing a chromatic glissando.

Among the objects of this invention relates the purpose of enabling one to play a chromatic glissando on a keyboard of the piano type. The glissando as generally used in piano playing comprises a direction used in pianoforte passages in which the back of the finger is made to slide along the tops of the white keys thereby producing a very brilliant scale. We have conceived of the desirability of producing a chromatic glissando with that class of musical instruments having keyboards similar to piano keyboards. In this type of keyboard the feat has heretofore been impossible because of the fact that the striking surfaces of the black keys are normally disposed at a higher elevation than the striking surfaces of the white keys.

In order to accomplish the purpose primarily stated we have developed various modifications by which a chromatic glissando may be played on a keyboard having keys of various heights such as a piano keyboard. The embodiment of the primary objects in these various modifications comprises further objects of our invention.

Other objects of the invention will appear hereinafter from a detailed description of the invention and from the drawings.

Fig. 1 is an elevation across a keyboard illustrating one means by which a chromatic glissando may be played.

Fig. 2 is a plan view of the arrangement shown in Fig. 1.

Fig. 3 is an elevation of a keyboard having auxiliary keys above the ordinary keyboard.

Fig. 4 is a plan view of the arrangement illustrated in Fig. 3.

Fig. 5 is an elevation of a keyboard with auxiliary keys placed beneath the ordinary keyboard.

Figs. 6, 7 and 8 are details illustrating the various elements used for producing the rollers illustrated in the remaining figures.

In order to play a chromatic glissando it is necessary that a keyboard be so modified or originally constructed to enable one to cause rapid and successive depression of keys of a chromatic scale, the movement being similar to the playing of a glissando.

To enable one to play a chromatic glissando we propose a line of finger receiving bearing surfaces at the same level for successive keys. To facilitate ease in playing, the bearing surfaces may be in the form of freely rotatable rollers, but plain flat surfaces could be substituted, if desired. We also contemplate the use of bearing surfaces of the same color or of different colors, such as black surfaces to correspond with the black keys and white surfaces to correspond with the white keys.

As far as the ordinary keyboard is concerned the drawings disclose the usual type of white keys 10 and black keys 11 mounted upon a balance rail 12 which is in turn secured to a key frame 13. These keys bear upon the felt washers at the lower ends of balance rail pins 14, 15 and the rear ends of each of the keys are connected to their respective piano actions through the abstracts 75

16. The simplest application of the invention is illustrated in Fig. 1 which shows a keyboard having each individual key provided with a rotatable roller 17 mounted thereon. The rollers are aligned on the same level and just to the rear of the vertical rear surface of the black keys and they may be mounted upon each successive key of the entire keyboard or upon any plurality of successive keys at one section of the keyboard. 80

Just to the rear of the line of rollers there is disposed a finger guide strip 18 having a recessed space 19 cut out so that the rear vertical surfaces and rear brackets of the rollers may be concealed. The finger guide strip 90 serves to facilitate locating the various rollers and also gives assistance in helping the player to keep his finger passing along a plurality of successive rollers. The ordinary arrangements for covering the keys, which is known as the fall board or cove, is not illustrated, but it is understood that when such an arrangement is used it is to be recessed so as to provide sufficient room above the finger guide strip for accommodating the hand while a chromatic glissando is being played.

It is readily understandable that finger guiding surfaces may be made in forms other than that of a roller, but we have illustrated a roller because we find that it gives the best results. The rollers may be made of solid material such as ivory, celluloid, ebony or in the manner illustrated in 100 105

Figs. 6, 7 and 8. The diameter of the core 20 of the roller is of a gradually reducing length from the ends of the core to its mid-section whereby a trough is formed and a player's finger may be comfortably accommodated. Each core is covered with a flexible cover similar to rubber tubing 21 which may be fastened to the core ends by glue or similar material if desired. The tubing 21 preferably has an internal diameter which is less than the external diameter of the core ends and greater than the mid-section diameter of the core. This relation produces a cushioning surface which is efficient as such by reason of the material used and because of the free space about the mid-section of the core. A pin 22, passing through the center of the roller, is journaled at its ends in a bracket 23 and the bracket is securely fastened to a key, Fig. 1, by means of a screw 24. It is apparent that the addition of the rollers to the ordinary keyboard would disturb balance of the keys and hence the touch of the piano, therefore, it is necessary that the touch be adjusted by rebalancing the keys with key leads as ordinarily done for different length keys. It is to be observed, however, that the arrangements for permitting the playing of a chromatic glissando may be placed inside the ordinary piano case without undo changes therein.

Figs. 3 and 4 illustrate another embodiment of our invention in that auxiliary keys 24, 25 are added above the keys 10 and 11 of the ordinary keyboard. These auxiliary keys are supported upon a balance rail 25 and balance rail pins 26 together with pins 27 serve to maintain the auxiliary keys in proper positions. The forward end of each of the keys is provided with a roller 17 similar to the roller which has just been described. This roller is mounted upon a pin or shaft 28 which extends forwardly from the end of an auxiliary key. The vertically extending flange of the key slip 29 may be used, if desired, for the purpose of holding the various rollers 17 upon their shafts 28. The rear ends of the auxiliary keys 24, 25 may be connected in any desired manner to respective piano actions. Each is illustrated as being associated with an abstract 30 by means of a guide screw 31 passing through lug 32 extending from the abstract. The lower end of this screw engages a button 33 carried by and at the rear end of an auxiliary key. Each auxiliary key has a spring 34 which prevents it from moving when a regular key is played in the ordinary manner. It is to be noted that the type of arrangement illustrated in Figs. 3 and 4 affords a mechanical advantage effective upon the auxiliary keys which is greater than the mechanical advantage obtainable by the arrangement illustrated in Figs. 1 and 2.

The piano keyboard illustrated in Fig. 5 is of the general type and has white keys 10 and black keys 11. In this arrangement the auxiliary keys 35 are pivotally mounted at 36 beneath the ordinary keyboard. The front end of each of these keys is connected with a wire 37 to a roller 38 which is mounted upon a bracket at the upper end of the wire. A hole 39 is provided in each of the ordinary keys in order to permit the wire to pass freely therethrough. A hole 40 likewise extends through the key frame for the same purpose. The rear end of each auxiliary key 35 has connected thereto a dowel or wire 41 having a cap 42 at its upper end. This cap is so fashioned as to contact a striker 43 on the under surface of the rear end of a ordinary key. Whenever the piano is played in the ordinary manner the cap 42 and the striker 43 will separate as each key is depressed. When playing a chromatic glissando the movement of the rollers 38 will be transmitted through wire 37, auxiliary key 35, wire 41 to the rear end of an ordinary key and thence to the abstract 44. If desirable the lengths and ratios of the lever arms of the auxiliary keys placed below the keyboard could be varied so as to enable the rollers to be placed in the key slip in front of the white keys and below their level. As in the embodiment illustrated in Figs. 3 and 4, it is possible to vary the mechanical advantage obtained on the auxiliary keys 35. For this purpose the pivot 36 could be moved either forwardly or rearwardly.

These various embodiments of my invention are adaptable or may be modified for the purpose of adapting them for use with any kind of a keyboard, whether it be for a grand piano, upright piano, player piano, reproducing piano or organ. In the various embodiments which we have shown it is not proposed to shorten the space allowed for the sharp or white key. However, it would be practical to do so and by so doing a greater degree of depression could be had and some persons might consider this advisable. Where player pianos or so-called reproducing pianos included a manual chromatic glissando it would be possible to arrange an electrical or pneumatic means of obtaining a chromatic glissando by having auxiliary ports or connections over which the finger might be passed. Our invention is capable of a wide variation and relationship of parts without departure from the nature and principle thereof, and we do not restrict ourselves unessentially in the foregoing or other particulars, but contemplate such alterations and modifications within the scope of the appended claims as may be found to be advisable.

What we claim is:

1. A chromatic glissando keyboard comprising a plurality of keys having finger

receiving surfaces, and a member extending lengthwise of the keyboard and having a portion thereof vertically disposed and adjacent a continuous edge of said finger receiving surfaces.

2. A chromatic glissando keyboard for a piano comprising a plurality of successive keys having finger receiving surfaces, and a finger guide strip running along the keyboard adjacent said finger receiving surfaces.

3. A piano keyboard having a roller mounted upon each key of said keyboard, said rollers being normally in alignment with their axes substantially parallel to each other, and a member extending lengthwise of the keyboard and having a portion thereof opposite one end of each of the several rollers.

4. A plurality of keys comprising sets of keys of different heights, an auxiliary keyboard having keys corresponding to keys of said sets of keys, one key of the auxiliary

key and one key of said sets of keys comprising a pair of keys, a plurality of actions, one of said actions being under the control of a pair of keys, and finger receiving means carried by the keys of said auxiliary keyboard whereby movement of a finger over the same produces successive actuation of said actions irrespective of their relation to keys of different heights of said sets of keys.

5. A piano keyboard, an auxiliary keyboard, one key of the auxiliary keyboard being provided for each key of the piano keyboard, a pair of said keys being adapted to control a common action, and means for enabling successive depression of a series of auxiliary keys irrespective of the association of any auxiliary key with a flat or sharp key of the piano keyboard.

In testimony whereof we hereto affix our signatures.

CHARLES FREBORG.
CASPER JELLY.
